UNITED STATES PATENT OFFICE.

CHARLES A. FOX, OF NEW YORK, N. Y.

COLLAPSIBLE BOX.

Application filed October 23, 1924. Serial No. 745,273.

To all whom it may concern:

Be it known that I, CHARLES A. FOX, a citizen of the United States, residing at New York city, county of New York, and State 5 of New York, have invented certain new and useful Improvements in Collapsible Boxes, of which the following is a specification.

This invention relates to improvements in 10 receptacles, and has particular reference to a collapsible box of the type disclosed in my previous Patent No. 1,498,441, dated June 17, 1924.

An object of the present invention is to 15 provide an improved box of simple and inexpensive construction wherein certain of the walls of one of the sections of the box are reinforced against collapsing when the box is in operative position by interweaving 20 an inner lining of said section with said side walls.

Another object is the provision of a lining for a section of the box which includes side walls each having end portions arranged 25 upon one side of a side wall of said section and another portion disposed on the opposite side of the latter side wall when the lining is in operative position.

The above and other objects will appear 30 more clearly from the following detailed description, when taken in connection with the accompanying drawings, which illustrate preferred embodiments of the inventive idea.

In the drawings—

Figure 1 is a perspective view of the box 35 in open position;

Figure 2 is a vertical longitudinal section therethrough;

Figure 3 is a plan view showing the box 40 partially collapsed;

Figure 4 is an edge elevation showing the box in completely collapsed position; and

Figure 5 is a fragmentary plan view, 45 partly in section, with the parts in the same position as shown in Figures 1 and 2.

The box of the present invention is of the kind commonly known as a telescoping box wherein one of the sections thereof is nested within the other when in closed position, but it is to be expressly understood that the invention is not limited to this particular type of box, the limits of the invention being defined by the appended claim.

The box proper is formed from a single 50 sheet of suitable material, such as cardboard or the like, and consists of a bottom section

6 and a top section 7 joined by an intermediate section 8, which forms the rear wall of the box when the sections are in closed position.

The bottom section 6 includes a front wall 9, the ends of which are overlapped by the front ends of the side walls 10, said overlapping ends being secured by suitable fasteners 11. The side walls 10 are scored, as indicated at 12, to permit of the side and front walls being folded inwardly and downwardly upon the bottom of the section 6 when it is desired to collapse the box.

A lining, generally indicated by the numeral 13, is provided for the section 6 and is formed from a single length of material, the intermediate portion 14 of which forms the rear wall of the bottom section and has its ends overlapped by the rear ends of the 75 side walls 10 and secured to said overlapping ends by suitable fasteners 15. When the box is in closed position the intermediate portion 14 forms a reinforcement for the intermediate section 8 to prevent said section from being readily collapsed due to outward pressure thereon.

The side walls 16 of the lining 13 extend forwardly from the intermediate portion 14 and approximately midway of their length. 85 Each side 16 is cut away along its bottom edge to provide a reduced forwardly extending tongue 17, the free extremity of which terminates in an enlarged locking head 18 for a purpose which will presently appear. It is proposed to interweave the side walls of the lining with those of the bottom section so that portions of the lining will be arranged interiorly of the side walls while other portions will be disposed exteriorly 90 of said side walls. For this purpose each of the side walls 10 is preferably provided intermediate its ends with a slit or notch 19 extending downwardly from the upper edge a distance substantially equal to the width 95 of the tongue 17 at its inner or rear end. At a point adjacent the forward end of each side wall 10 the same is provided with a vertically disposed slot 20. When setting up the box the portion of each side wall 16 of the lining at the inner end of the tongue 17 thereof is inserted into the slit 19 so as to extend a portion of the tongue exteriorly of the side wall 10. The head 18 of the tongue 100 is then inserted through the slot 20 so that said head will be disposed on the inner side of the side wall 10 and due to the enlarge-

- ment of said head, it will be apparent that the same cannot be accidentally withdrawn from the slot 20 when the lining is in operative position. Also the head 18 will overlap the front scored portion 12 of the side wall and will thus brace the side wall at said scored portion. By thus constructing and disposing the lining, it will be apparent that the side walls thereof will be interwoven with the side walls 10 of the section and will reinforce and brace the latter side walls against collapsing when the box is in its operating position. The box may be knocked down or collapsed by withdrawing the head 18 of the tongue from the slot 20 and then detaching the inner portion of the tongue from the slit 19. After this is done the side walls 16 may be swung against the intermediate portion 14 of the lining and overlapped with each other, as illustrated in Figure 3. Following this operation the front and side walls 9 and 10 of the bottom section may be folded inwardly upon the bottom of said section.
- 25 The top section 7 includes the side walls 21 overlapped at their free ends with the adjacent ends of the front wall 22 of said section and secured to said front wall by suitable fasteners 23 to form reinforced corners for the section. At the inner ends of the side walls 21 adjacent the intermediate section 8 said walls are creased or folded, as indicated at 24, to permit of the side

walls being collapsed to the position shown in Figure 3 and said side walls are additionally scored, as indicated at 25, to also aid in the collapsing of said walls, together with the front wall 22.

With the top and bottom sections and the lining collapsed the top section may be folded over upon the bottom section, as indicated in Figure 4, so that when the box is not in use the same will form a compact structure which will occupy a minimum space in storage.

45 What is claimed is:

In a collapsible box, a bottom section including side walls, and a lining for said section also including side walls each having a portion engageable with one side of an adjacent side wall of said section, and another portion formed into a locking tongue, the major portion of which is engageable with the opposite side of said side wall and the free extremity of said tongue being engageable with the first named side of the latter wall, each of the side walls of the section having a slit and a slot, said slit receiving the portion of the adjacent side wall of the lining contiguous to the inner end of said locking tongue, and the slot receiving the free extremity of said tongue.

55 60 65 In testimony whereof I have affixed my signature.

CHAS. A. FOX.
